CLAIM

The ornamental design for short pants, as shown and described.

DESCRIPTION

FIG. 1 is a front, top, right side perspective view of short pants, showing my new design;

FIG. 2 is another front, top, right side perspective view thereof;

FIG. 3 is a rear, bottom, left side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged view of detail "10" identified in FIG. 1.

The dashed broken lines in the figures illustrate portions of short pants that form no part of the claimed design. The dash-dot-dash broken lines in FIGS. 1 and 10 depict the bounds of the enlarged views and form no part of the claimed design.
